W. H. Reid

UNITED STATES PATENT OFFICE

JOSEPH BRIGIDA, OF NEW YORK, N. Y.

ELECTROLYSIS DEVICE

Application filed February 12, 1930. Serial No. 427,718.

This invention has reference to devices for facilitating the application of the needles used in the operation of electrolysis, for removing superfluous hair or blemishes from persons.

The object of the invention is to provide a device that will accommodate a comparatively large number of cables with needles of this character on their extremities, and which cables can have their available length where extending from the casing, adjusted to facilitate their application to various parts of the person being treated.

A further object is to provide means for accommodating the slack in the length of the cable when the amount of the cable drawn out of the casing is changed.

In the accompanying drawing showing embodiments of my invention:

20 Fig. 1 is a perspective view of the device with the cover partly broken away.

Fig. 2 is a transverse section of the device shown in Fig. 1.

Fig. 3 shows the rheostat detached.

25 Figs. 4-8 show enlarged the clutch connection for the needle at the end of the cable.

Fig. 9 indicates the several rheostats and their connection with the cables.

As shown in the drawing I provide a casing 20 having a bottom wall 2 and a rear wall 3 with end walls 4 and a flat top wall 5. At the front is a short inclined wall 6 and an inclined wall 7 extends forward and upward from the top wall 5 and may project a short distance down into the casing as indicated in Fig. 2. At the upper edge of this inclined top wall 7 is hinged a cover 8 that will rest at its lower edge against the front wall 6 and close the casing, but when swung up as indicated in Fig. 1 will expose the casing bottom at inclined wall 7 and the front wall 6.

A number of cables 9 that extend from a common source of supply of current from conductors in the casing, and which are supported whereby they may be drawn back into the casing to take up slack in the cable between the casing and the person being treated.

As shown the top wall 5 is provided with a series of openings 10, 10, extending across the top as indicated in Fig. 9. Opposite these

openings 10 the inclined wall 7 is provided with a similar row of openings 11, 11. Each of the cables 9 having the needle 12 connected to its free end by the clutch 13 is passed first through the openings 11 in the inclined wall 55 from the inner face of this wall, and thence down through the openings 10 in the top wall 5. It will thus be seen that the slack in the cable when not in use can be caused to rest inside of the casing with the lid 8 in the closed position as indicated in Fig. 2. And when it is desired to use the needle the lid is raised as shown in Fig. 1 and the cable drawn out. If it has too much slack the cable is drawn back from the exposed portion lying between the inclined top 7 and the top 5, as indicated in broken lines in Fig. 1. By this means the length of any of the cables can be readily adjusted.

The current from the battery or other source is received at a binding post 14 extending through the rear wall 3 forming a conductor 15. The several cables are connected with this binding post, but preferably through several rheostats. As shown 75 a rheostat 16 is mounted on the top wall 5 with one wire 17 connected with the binding post 14, and from the outlet 22 of the rheostat, lead four cables, 9, 19, 20 and 21. A second rheostat 26 connects with the binding post 14 by a wire 27, and has three outlet wires or cables 28, 29 and 30. A third rheostat 31 connects with the binding post by a wire 32 and has three outlet cables 33, 34 and 35. It will thus be seen that three 85 groups of the cables are provided, each controlled separately by a rheostat. Obviously the amount of current that would pass to the needles of each group can be varied so that one group would receive a greater amount 90 of current than another group.

Means are further provided for connecting the wire 12 with the cable 9 and others, shown in the form of a kind of clutch member, in Figs. 4-8. The clutch member comprises a sleeve member 36 having the cable 9 secured in one end, and the other end has the bore screw threaded which is conical at the end 37, see Fig. 4. The needle holding member is shown in Figs. 4, 5 and 6 100

as comprising a threaded shank 38 with a small bore 39 to receive the needle 12. Beyond the shank is a conical knurled head 40 whose tapered portion 41 will engage the conical bore 37 when the head is screwed into the sleeve 36 as shown. The head may have one or more slots 42 extending into the axis from one side and thereby forming an opening throughout the axis of this member, that registers with the head bore 39. The head 40 may also have other slots 43 and 44 extending into the axis, that will facilitate the compression of the head on the needle 12 when the head is screwed into the sleeve as shown. It will be understood that the shank of the head is screwed in a short distance and the needle inserted until its inner end passes into the cable 9 that in this art is formed of a tinsel core. The screwing in of the head will cause it to bind on the needle and securely hold it in position, projecting into the conductor. Obviously when the head is screwed out the needle will be released and can be substituted. It will be further seen that a long slender needle of much thinness can be employed, and the needle will be securely held, and does not require a thickened shank or extension.

In Fig. 7 another form of clutch is shown, in which the shank 45 of the head has a slot 46 from the head extending back into the shank instead of the bore 39 as shown in Fig. 5. This will make a simpler construction, and this slot will form an opening all the way back in the axis of the member.

In Fig. 8 a similar arrangement is shown, but the shank 47 of the head has a slot 48 extending in from the rear and across the axis until it meets the slot 49 in the head portion, whereby an opening is provided through the member in the axis.

It will be understood that the conductor 15 connects with one pole of a suitable battery or source of current, and that the other pole of the battery is connected with the person being treated, so that if placed on the wrist or arm, the circuit will be completed from the needle through the person.

An arm 23 leads rearward from the casing and is supported from a bar 25 by a clamp 24 that will permit a kind of universal movement to support the casing in convenient position for use.

What I claim is:

In a device of the character set forth, the combination of a casing composed of a bottom and sides and an apertured flat top wall, an apertured wall at one side of the casing inclined upwardly from the adjacent flat top wall, a lid hinged to the upper part of said inclined wall and normally extending downward to engage the end walls and a short lower side wall to thereby close the casing, a set of cables inside of the casing, an electrolytic needle on the free end of each

cable, a binding post in the rear wall of the casing to carry one conductor into the cables, said cables passing upwardly through the flat top at openings therein and thence through openings in the said inclined wall to bring the cables back into the casing, whereby upon raising the hinged lid the cables can be withdrawn from the casing for use and the available length of the cables can be adjusted by drawing them forward and back through the said inclined wall.

Signed at New York city, N. Y., on February 7, 1930.

JOSEPH BRIGIDA.
